UNITED STATES PATENT OFFICE.

GUSTAVE H. JANTZ, OF WYOMING, OHIO.

WRINGER.

1,408,807.

Specification of Letters Patent.

Patented Mar. 7, 1922.

Application filed July 31, 1919. Serial No. 314,436.

To all whom it may concern:

Be it known that I, GUSTAVE H. JANTZ, a citizen of the United States, residing at Wyoming, in the county of Hamilton and State of Ohio, have invented certain new and useful Improvements in Wringers, of which the following is a specification.

My invention relates to wringers of the character of those employing opposed wringer-rolls between which the goods are arranged to be passed for expressing the water.

It is the object of my invention to provide new and improved means whereby the opposed rolls between which the goods are arranged to pass, may be instantly separated for preventing injury either to the goods or to the operator; further, to provide a breakdown frame for a wringer; further, to construct the frame of the machine in a plurality of parts and provide mounting means on the respective parts for the wringer-rolls, and means whereby movement is obtained of one frame-part with relation to the other for relieving the pressure between the wringer-rolls; and, further, to provide such means in such manner that the tensioning means acting to cause pressure between the wringer-rolls form a part of one of said frame-parts.

It is the object of my invention, further, to provide novel means whereby to permit separation between the wringer-rolls when the wringer is to be idle, or to prevent accident to the goods or to the user, or to relieve pressure in case of accident.

The invention will be further readily understood from the following description and claims, and from the drawings, in which latter:

Fig. 1 is a front elevation of my improved device, partly broken away.

Fig. 2 is a plan view of the same, partly broken away.

Fig. 3 is a horizontal cross-section of one end of the wringer, taken on the line 3—3 of Fig. 4, and partly broken away.

Fig. 4 is an end elevation of my improved device.

Fig. 5 is a similar view, partly broken away, and showing the lower frame-part in vertical section on the line 5—5 of Fig. 3.

Fig. 6 is a rear elevation of one end of the wringer; and,

Fig. 7 is a vertical section taken on the

line 7—7 of Fig. 4, to show the releasing means for the latch.

The lower or base part of the wringer-frame is exemplified at 21, and may be provided with suitable means for attaching the wringer to a support. These means may be suitable well-known clamping means for attaching the same direct to a tub or a power-driven washing machine, but I have preferred to show the lower wringer-frame provided with pedestals 22, having base-flanges 23, through which suitable screws or bolts may pass for attaching to a suitable support. The pedestals are connected by a cross-rod 24, suitably secured to each of said pedestals, as by providing the cross-rod with reduced threaded ends 25, passing through holes in lugs 26 on the respective pedestals, the pedestals being clamped thereto between shoulders on said cross-rod and nuts 27 screwed over said threaded ends.

The lower or attaching frame-section comprises suitable bearings 31, in which the shaft 32 of the lower wringer-roll 33 is arranged to rotate. The lower shaft 32 may be extended, for receiving a suitable turning means thereover for either power or manual operation. I have exemplified power driven operating means, shown as a bevel-gear 34, suitably secured to the shaft 32 for turning the same, and suitably driven.

A movable section of the wringer-frame may be movably arranged with relation to the attaching frame-section. The movable frame-section comprises bearings 36, in which the shaft 37 of the upper wringer-roll 38 is arranged to rotate.

Driving means may be provided between the shafts, if desired, and are exemplified by providing the shaft 32 at each end of the roll 33 with a cog-wheel 41 fixed to said shaft, and by providing the shaft 37 at each end of its roll with a cog-wheel 42. The cog-wheels are preferably provided with two sets of interengaging comparatively deep teeth, in usual manner, for maintaining driving relation between the rolls throughout the usual cooperative positions of the rolls when goods, clothes, or the like, are being passed between the same, for expressing water or moisture therefrom. Suitable gear-covers 44, 45, may be provided. They may be suitably secured to the respective bearings 36, 31, as by screw and nut connec-

tions 46, 47. The gear-covers 44 move with the upper bearings.

I have found it desirable to permit separation between the rolls, for instance, when the operator has finished the use of the machine and the same is to be idle for a time, and especially to prevent accident to the goods or to the operator, or to relieve pressure in case of accident, for instance, for permitting separation between the rolls when the goods are becoming bunched, or buttons are being fed while extending crosswise between the rolls, and injury to the operator, for instance, on accidental catching of the fingers or hair or part of the clothes of the operator between the rolls to prevent danger of having the same drawn between the rolls, and to release the same. Such separating means are especially desirable when an electric or other power is employed for rotating the wringer-rolls.

For accomplishing the objects mentioned, I have preferred to so construct the frame of the wringer that movement may be had between the frame-sections which support the respective opposed wringer-rolls, forming what I term a break-down frame. I have provided means whereby the tensioning mechanism, for causing pressure between the rolls while the goods are passing therebetween, is part of one of the frame-sections.

In the present exemplification, I have provided springs 51, which are arranged to exert pressure between the rolls, and interpose these springs between two parts of the movable section of the wringer-frame, one of the latter parts being pivoted to the relatively stationary section of the wringer-frame, and the other of the latter parts arranged to support the wringer-roll 38.

The lower frame-section is provided with pivot-lugs 53, and the upper frame-section comprises pivot-parts 54, from which pivot-lugs 55 extend. The lower frame-member, at each end of the frame, is provided with a pair of the lugs 53, between which one of the lugs 55 of the upper frame, at each end of the machine, is received, a pivot-bolt 56 being received through the pivot-holes of said lugs at each end of the frame.

The spring 51 is fixed to the pivot-part 54, as by rivets 58. The spring is shown as a bow-spring, with the ends of the spring adjacent to each other, the pivot-part being secured to the spring at one end or leaf of the bow. The other end or leaf of the bow has the bearing-part 59 of the upper frame-member secured thereto, as by rivets 60.

The movable frame-member is provided with a catch 65, preferably at each end thereof, with which a latch 66, preferably at each end thereof, is arranged to engage, for holding the roller-bearings in mating relation for coaction between the rolls. The catch is instanced as formed by the edge of the

bent end 67 of the spring. Each of the latches is pivoted on a pivot 68 shown as a pin received through the bearing 69 therefor in the latch and in bearings 70 in the lower frame-member. A spring 71 normally urges the latch against a stop 72, shown as a pin.

Means are provided for quickly releasing the latching means. I prefer to extend these means crosswise of the machine, so that the same may be grasped at any position, and preferably arranged to be pushed or pulled at any position without an actual grasping thereof, and I prefer that the release of the latch may be had by movement of the releasing means in either of opposite directions, so that the release may be instantly and effectually accomplished.

These releasing means are shown as a lever 73 at each end of the frame, pivoted by a pivot 74 at each end to the lower frame-section. The pivot may be a threaded shank extending from the pedestal and having a pivot-bearing 75 of the lever journaled thereabout. A friction-washer 76 is received about the shank between the bearing and a nut 77, for yieldingly holding the lever in assumed positions. A connecting-bar 78, rigidly secured to the upper ends of the levers, connects the levers, accomplished, for instance, by having a bearing 79 at the upper end of each lever, through which a reduced part 80 of the connecting-bar is received, the bearing being clamped against the shoulder 81, thus formed, by a clamp-nut 82, received about the threaded end of said reduced part.

The body of the latch may be extended, and the latch is provided with lugs 85, 86, which are at opposite positions with relation to the pivot 74. The lever is provided with coacting lugs 87, 88, which coact with the lugs on the latch, the lugs on the lever being exemplified as at the same sides of the lugs on the latch. The latch and the catch on the movable frame-member are preferably located in a recess 91, shown as located between the lugs or flanges, 53, and a rear wall 89, so as to inclose the same. The lugs on the latch may extend through slots 92, 93, in the lug or flange 53, so as to be placed in range with the lugs on the lever. There is a similar construction at each end of the wringer-frame.

When, now, it is desired to cause relief of pressure between the wringer-rolls, for instance, in case of accident, a movement of any part of the lever-frame in either of opposite directions, in the present instance either forwardly or backwardly, will cause substantially simultaneous release of both latches, whereby the movable frame-section is permitted to swing on its pivots so as to relieve pressure between the wringer-rolls.

The upper wringer-shaft 37 is preferably held in place in its bearing, so as to be re-

tained therein when the movable frame-section is moved, accomplished, for instance, by providing a pin 95 for each of the bearings, arranged to be received in the bearings and 5 to hold the shaft in place in its bearings.

The swinging back of the upper roll is accomplished with a quick movement, as the spring aids in the separation for causing a bounding of the upper roll away from the 10 lower roll, so that complete separation between the rolls is immediately effected to prevent a continuation of pressure between the rolls.

If it is desired to replace the movable roll 15 in coactive relation with its opposed roll, it is only necessary to swing the movable frame so as to cause reengagement of its catches with the latches. The lever-frame may, during this movement, be held in up- 20 right position, so as to prevent interference thereby with the engagement of the latches with the catches, accomplished by providing the friction-washers 76.

The reengagement of the latches and 25 catches may be accomplished in the present exemplification, by swinging the movable section to place the rolls in cooperative positions and by downward pressure upon the upper roll or upon the movable section ad- 30 jacent to the front part thereof, or by up- 35 ward pressure on the springs at the rear part thereof, or, if desired, the bearings 36 may be provided with lugs 96, between which a cross-rod 97 is rigidly secured, by 40 means of which the said bearings may be pressed toward their opposed bearings for bringing the catches and latches into reengaging relation. The cross-rod 97 may be provided with reduced threaded ends 98, 45 the lugs 96 being clamped between shoulders 99 on said rod and nuts 100 on said threaded ends.

When wringing the goods, the goods pass 45 between the wringer-rolls in a direction lengthwise of the horizontal plane in which the coacting parts of the faces of said wringer-rolls are located, and the movable wringer-roll has movement lengthwise of said path in its releasing movement.

50 It is obvious that changes may be made in the construction and arrangement of the parts I have preferred to show, without departing from the spirit of my invention.

Having thus fully described my invention, 55 what I claim as new and desire to secure by Letters Patent, is:

1. A break-down frame for a wringer comprising a plurality of frame-parts, each including bearing means for a wringer-roll, 60 pivot means between said frame-parts whose pivotal axis is substantially parallel with the axes of said bearing means, one of said frame-parts comprising spring means as part of its frame-structure for exerting pressure between the wringer-rolls,

said spring means located between said pivot means and the bearing means of said one of said frame-parts, latching means between said frame-parts, and quick-releasing means for said latching means, where- 70 by quick separating movement between said wringer-rolls is caused by the quick release of said latching means.

2. In a wringer, the combination of a frame-section, a roll mounted therein, a sec- 75 ond frame-section movable with relation to said first-named frame-section, said second-named frame-section comprising separated frame-parts connected by tensioning means for a coacting roll, bearing means on one 80 of said frame-parts for said coacting roll, jointing means between the other of said frame-parts and said first-named frame-section, connecting means between said last-named frame-part and said first-named 85 frame-section for arranging said rolls in coactive relations with pressure between them, and quick-release means to release said connecting means, whereby to cause rebound by said tensioning means of said separated 90 frame-parts and said tension means as an entity away from said first-named roll.

3. In a wringer, the combination of a frame-section, a roll mounted therein, a sec- 95 ond frame-section mounted to move up- 100 wardly and rearwardly with relation to said first-named frame-section, a coacting roll controlled thereby, connecting means between said frame-sections for arranging said rolls in coactive relations, and releas- 105 ing means comprising an operating part movable in opposite directions and having releasing connection with said connecting means in either direction of its movement, and constructed and arranged whereby 110 movement of said operating part in either of opposite directions acts to release said connecting means.

4. In a wringer, the combination of a frame-section, a roll mounted therein, a 110 second frame-section pivoted to said first-named frame-section, a coacting roll controlled thereby, latching means for latching said frame-sections in cooperative relations, and releasing means for said latching means 115 comprising a cross-bar above the arc of the movement of said second-named frame-section and oppositely actuatable connections with said latching means, and constructed and arranged whereby the roll controlled by 120 said second-named frame-section is arranged to move in an arc between the pivot of said second-named frame-section and said cross-bar upon release of said latching means.

5. In a wringer, the combination of a 125 lower frame-section, an upper frame-section, said upper frame-section comprising a pivot-part, a roll bearing part and a bow- spring between said parts, a pivot between said pivot-part and said lower frame-section, 130

latching means between said pivot-part and said lower frame-section, and releasing means for said latching means.

6. In a wringer, the combination of a lower frame-section comprising bearing means for a lower wringer-roll, an upper frame-section comprising bearing means for an upper wringer-roll and tensioning means for said last-named bearing means formed as part of the frame-structure of said upper frame-section, pivot means between said frame-sections whose pivotal axis is substantially parallel with the axes of rotation of said wringer-rolls, latching means for said upper frame-section between said pivot and said roll-bearings, and quick-release means for said latching means.

7. In a wringer, the combination of a lower frame-section comprising bearing means for a lower wringer roll, an upper frame-section comprising bearing means for an upper wringer-roll, pivot means between said frame-sections whose pivotal axis is substantially parallel with the axes of rotation of said wringer-rolls, latching means for said upper frame-section between said pivot and said roll bearings, and oppositely acting releasing means for said latching means, said releasing means comprising an operating part, movable in opposite directions to release said latching means.

8. In a wringer, the combination of wringer-rolls, and means at each end of said wringer-rolls comprising a lower relatively stationary bearing, an upper movable bearing, a pivot-lug extending from said lower bearing, a pivot-part, a pivot between said pivot-part and said pivot-lug, a bow-spring whose ends are in adjacency, said pivot-part and said second-named bearing secured to said respective ends of said bow-spring, latching means between said lower bearing and said pivot-part, and releasing means for said latching means.

9. In a wringer, the combination of wringer-rolls, and means at each end of said wringer-rolls comprising a lower relatively

stationary bearing, an upper movable bearing, a pivot-lug extending from said lower bearing, a pivot-part, a pivot between said pivot-part and said pivot-lug, a bow-spring whose ends are in adjacency, said pivot-part and said second-named bearing secured to said respective ends of said bow-spring, latching means between said lower bearing and said pivot-part, and releasing means for said latching means, and a cross-piece connecting the releasing means at the respective ends of said wringer-rolls.

10. In a wringer, the combination of a roll-bearing, a pair of pivot-lugs extending therefrom, an upper bearing, a pivot-lug operatively connected therewith and received between said first-named pivot-lugs, a catch therefor between said first-named pivot-lugs, a latch for said catch between said first-named pivot-lugs, and a releasing lever pivoted with relation to said lower bearing, said releasing lever and said latch provided with coacting parts whereby to release said catch by movement of said lever in either of opposite directions.

11. In a wringer, the combination of a roll-bearing, a pair of pivot lugs extending therefrom, an upper bearing, a pivot-lug operatively connected therewith and received between said first-named pivot-lugs, a catch therefor between said first-named pivot-lugs, a latch for said catch between said first-named pivot-lugs, a releasing lever pivoted with relation to said lower bearing, said releasing lever and said latch provided with coacting parts whereby to release said catch by movement of said lever in either of opposite directions, and a bow-spring having adjacent ends, said second-named pivot-lug and said second-named bearing secured to said respective ends.

In testimony whereof, I have hereunto signed my name in the presence of two subscribing witnesses.

GUSTAVE H. JANTZ.
